UNITED STATES PATENT OFFICE.

ERNEST T. BECK, OF MERIDEN, CONNECTICUT, ASSIGNOR TO INTERNATIONAL SILVER CO., OF MERIDEN, CONNECTICUT, A CORPORATION OF NEW JERSEY.

DESIGN FOR A DISH OR SIMILAR ARTICLE.

Application filed September 4, 1926. Serial No. 18,975. Term of patent 14 years.

To all whom it may concern:

Be it known that I, ERNEST T. BECK, a citizen of Germany, residing at Meriden, in the county of New Haven and State of Connecticut, have invented a new, original, and ornamental Design for a Dish or Similar Article, of which the following is a specification, reference being had to the accompanying drawing, forming part thereof.

ing my new design, it being understood that the border decoration is continued around the entire circumference of the article and that the surface ornamentation at the end and side is repeated.

Figure 2 is an edge view of the same.

I claim:

The ornamental design for a dish or similar article as shown.

ERNEST T. BECK.
